CLAIM

The ornamental design for a turbo heater blade, as shown
and described.

DESCRIPTION

FIG. 1 is a front elevational view of a turbo heater blade
showing my new design;

FIG. 2 is a back elevational view thereof;

FIG. 3 is a first side elevational view thereof;

FIG. 4 is a second side elevational view thereof;

FIG. 5 is a third side elevational view thereof;

(Continued)

FIG. 6 is a fourth side elevational view thereof; and, FIG. 7 is a front perspective view thereof. The broken lines shown in the drawings depict unclaimed hub portions of the turbo heat blade, are for illustrative purposes only and form no part of the claimed design. The surfaces shown between the solid lines and the broken lines form no part of the claimed design.
